UNITED STATES PATENT OFFICE

105,180

DESIGN FOR A RADIATOR VALVE

Charles A. Olson, Geneva, Ill., assignor to Crane
Co., Chicago, Ill., a corporation of Illinois

Application November 13, 1936, Serial No. 65,888

Term of patent 14 years

To all whom it may concern:

Be it known that I, Charles A. Olson, a citizen of the United States, residing at Geneva, in the county of Kane and State of Illinois, whose post-office address is 728 Shady Avenue, Geneva, Illinois, have invented a new, original, and ornamental Design for a Radiator Valve, of which the following is a specification, reference being had to the accompanying drawing, forming part thereof.

Fig. 1 is a plan view of the valve showing my new design.

Fig. 2 is a side view.

Fig. 3 is a rear view.

The characteristic feature of my design consists in the angular tapering indicator with the arcuately slotted stop plate.

I claim:

The ornamental design for a radiator valve substantially as shown and described.

CHARLES A. OLSON.
